UNITED STATES PATENT OFFICE.

JOEL JENKINS, OF MOUNT VERNON, NEW YORK.

SNAP-HOOK.

SPECIFICATION forming part of Letters Patent No. 229,137, dated June 22, 1880.

Application filed April 24, 1880. (No model.)

To all whom it may concern:

Be it known that I, JOEL JENKINS, of Mount Vernon, in the county of Westchester and State of New York, have invented a new and Improved Snap-Hook; and I do hereby declare that the following is a full, clear, and exact description of the same, reference being had to the accompanying drawings, and to the letters of reference marked thereon, making part of this specification.

This invention is in the nature of an improved snap-hook; and the invention consists in a snap-hook made from a single piece of wire and having a twisted shank, in the manner hereinafter described.

In the accompanying sheet of drawings, Figure 1 represents a side view of my improved snap-hook, and Fig. 2 a front view of the same.

Similar letters of reference indicate like parts in both figures.

My hook is constructed entire from a single piece of wire, which is turned once or twice, as at *a*, to form the spring. From this turn or spring the wire is continued in two branches, *A* and *B*, nearly parallel with each other. One of these branches, *A*, is doubled to form an eye, *b*, with parallel sides, and twisted and curved at *c* to form a hook, *C*, and shank, its end being finally secured to the branch, as at *d*. The other branch, *B*, is extended somewhat beyond the eye, and it is turned up to form on its end a head, *e*.

Now, my snap-hook being in this way constructed, it is operated by inserting the article to be attached to it (as the ring of an eyeglass or other article) in the hook *C*, after which the branch *B* is pressed down until the head *e* on its end is beneath the eye *b*, when, by the elastic force of the spring *a*, this head *e* is forced

up between the sides of and within the eye, 40 locking the head within the eye and preventing its displacement therefrom until the branch *B* is again depressed, pushing the head *e* from the eye to remove the eyeglass or other article attached to it.

This construction of a snap-hook not only produces a hook that is easily operated, but it is cheaply made and strong, and supplies a want long felt—that is, a cheap and easily-adjusted means of attaching eyeglasses and 50 similar articles to their guards.

The snap-hook hereinbefore described is equally applicable to many purposes for which the more expensive catches are now employed.

It will be seen that from the construction of 55 my snap-hook, no matter how great the strain may be on the hook itself, the branch *B* cannot be detached from the hook as long as its head *e* remains locked in the eye *b*, and that the office of this eye is not only to secure the end 60 of the branch *B* to the hook, but it also stiffens the hook itself and prevents it from being bent out of shape by the strain that may be applied to it, and by twisting the shank of the hook it is rendered stiffer and better able to resist 65 strain.

Having now described my invention, what I claim as new, and desire to secure by Letters Patent, is—

A snap-hook constructed from a single piece 70 of wire and bent to form a spring, *a*, eye *b*, with parallel sides, tongue or branch *B*, with head *e* at the end thereof, and a twisted shank, substantially as and for the purpose described.

JOEL JENKINS.
